UNITED STATES PATENT OFFICE.

JOHN S. MUCKLÉ, OF PHILADELPHIA, PENNSYLVANIA, ASSIGNOR TO
STANDARD ELEVATOR INTERLOCK COMPANY, OF PHILADELPHIA,
PENNSYLVANIA, A CORPORATION OF PENNSYLVANIA.

LOCKING MECHANISM FOR ELEVATORS.

No. 811,427.

Specification of Letters Patent.

Patented Jan. 30, 1906.

Application filed October 28, 1904. Serial No. 230,357.

To all whom it may concern:

Be it known that I, JOHN S. MUCKLÉ, a citizen of the United States, residing in Philadelphia, Pennsylvania, have invented certain 5 Improvements in Locking Mechanism for Elevators, of which the following is a specification.

My invention relates to certain improvements in mechanism for releasing the landing-doors of elevators and for locking the operating mechanism of the elevator.

The object of my invention is to dispense with any mechanism within the car or, in fact, above the floor of the car, and to so design the mechanism that it can be mounted under the car and directly coupled to the door-releasing device.

Referring to the accompanying drawings, Figure 1 is a sectional elevation of sufficient 20 of an elevator-car to illustrate my invention. Fig. 2 is a sectional plan view on the line 2 2, Fig. 1; and Fig. 3 is a sectional elevation looking in a direction opposite to that shown in Fig. 1.

25 A is the elevator-car, and mounted in suitable bearings under the floor of the car is an operating-shaft B. To this shaft is attached the operating-lever B' in the ordinary manner, or the shaft may be geared to an operating-wheel, if desired.

30 The means for operating the shaft and the means for transmitting the motion from the shaft to the valve mechanism or other controlling mechanism in the basement of the building forms no part of my present invention.

35 C is a frame having a plate c, which is bolted or otherwise secured to the under side of the elevator-car. This frame has a bearing c', through which the shaft B passes, and on one side of the frame is a train of plain gears, and on the opposite side is a train of elliptical gears.

Secured to the shaft B is a segment D. 40 The teeth of this segment mesh with the teeth of a pinion d on a stud E, projecting from the frame C. Secured to the hub of the pinion d is a gear-wheel d', which meshes in turn with a pinion e, secured to a shaft F, 45 having its bearings in the frame C and carrying at its opposite end and on the opposite side of the frame an eccentric gear-wheel G, which meshes with a second eccentric gear-wheel H,

carried by a stud H', projecting from the frame C. The eccentric gear-wheel H' has a 55 pin h, to which is attached a connecting-rod I, which is adjustably secured to a head I' having a block i, through which passes a pin m on a plunger M, mounted in a guide-plate N, secured to the under side of the car. 60

All the above-described mechanism is situated under the body of the car and being simple and compact cannot readily be disarranged and cannot be tampered with by any one within the car. 65

The plunger M has a roller m in the present instance which is arranged to act upon a latch s, pivoted to a plate secured to the wall of the elevator-well. This latch engages with a projection on the landing-door S when 70 the said door is in its closed position and locks the door. On one side of the plunger M is a flange m', and pivoted to the plate on the wall of the elevator-well is a locking-lever s', which engages the flange m' of the plunger 75 as soon as the door is opened. The locking-lever is weighted and is held out of the path of the plunger by the door when it is in its closed position. This particular door-locking mechanism is illustrated in the patent 80 granted to me on the 20th day of September, 1904, No. 770,601, and therefore needs no further detailed description.

In order that the plunger may be reversed to fit right or left hand doors, it is provided 85 with a flange m² at the rear similar to the flange m', and when the plunger is reversed this flange will be in proper position to be engaged by the locking-lever s'.

The type of plunger illustrated forms no part 90 of my present invention, as it is set forth in the patent granted to me on the 11th day of April, 1903, No. 787,208.

While I have shown the mechanism attached directly to the operating-shaft of the 95 controlling means, the shaft shown may in some instances be geared to the operating-shaft where it is not desirable or possible to make a direct connection, and in some instances the segment D may mesh directly 100 with a gear on the shaft F.

The operation of the device is as follows: When the operator moves the lever to a central position, if a lever is used, the car is brought to a standstill, and if the floor of the 105 car is at a landing the plunger is forced out

by the movement of the segment. The plain and elliptical gearing will actuate the door-locking lever s and allow the door S to be opened either by power or automatic means, and as soon as the door is opened a locking-lever s' on the elevator-well will immediately engage the flange on the plunger and prevent its withdrawal, and consequently will lock the operating-lever in its central position. In order to release the lever, the elevator-door S will have to be closed. This closing of the elevator-door shifts the plunger-locking lever s' , and by moving the operating-lever to the right or left, according to the direction in which the car is to be moved, the plunger is withdrawn from the door-locking lever s and the door is immediately locked and held in its closed position until the car is again at the landing.

20 I claim as my invention—

1. The combination in door-locking mechanism for elevators, of a plunger mounted under the floor of a car, a shaft under the car and controlling the operating mechanism of the car, gearing mounted under the car and connecting the shaft with the plunger, and a door-lock and a plunger-lock on the elevator-well, substantially as described.

2. The combination in a door-locking mechanism for elevators, of a plunger mounted under the floor of the car, a frame also mounted under the floor of the car, a shaft controlling the operating mechanism of the car, elliptical gears carried by the frame connected to the plunger and geared to the operating-shaft, and door-locking mechanism on the elevator-well arranged to be acted upon by the plunger, substantially as described.

3. The combination of an elevator-car, a plunger, an operating-shaft for the controlling mechanism and a frame, all mounted under the floor of the car, gears carried by the frame, a rod connecting the said gearing to the plunger, a segment on the operating-shaft meshing with the said gearing, and door-locking mechanism on the elevator-well arranged to be actuated by the plunger, substantially as described.

4. The combination of an elevator-car, a frame secured to the car under the floor thereof, elliptical gears on one side of the frame and plain gears on the opposite side of the frame, a shaft mounted on the frame, a plain gear and an elliptical gear carried thereby, an op-

erating-shaft mounted in bearings under the floor of the car, means for operating the said shaft to start and stop the car, a segment on said shaft meshing with the plain gears, a plunger, a slide therefor, a rod connecting the plunger with one of the elliptical gears, and a door-locking device actuated by the plunger, substantially as described.

5. The combination of an elevator-car, a frame secured to the under side of the car, an operating-shaft for controlling the starting and stopping of the car, a bearing for said shaft carried by the frame, a segment on the shaft, a pinion carried by a stud on the frame, a gear-wheel mounted on the hub of the pinion, a shaft having its bearings in the said frame, a pinion carried by the shaft and meshing with the gear-wheel, an elliptical gear-wheel mounted on the opposite end of the shaft, a second stud on the frame, a second elliptical gear-wheel on said last-mentioned stud and meshing with the first elliptical gear-wheel, a pin on the second elliptical gear-wheel, a plunger, a rod connecting the plunger with the pin on the second elliptical gear-wheel, and a door-locking device actuated by the plunger, substantially as described.

6. The combination in means for releasing a landing-door when the elevator-car is at the landing and locking the operating mechanism when the door is opened, of an elevator-car, a frame secured to the under side of the car, gearing carried by said frame, an operating-shaft also under the bottom of the car, a segmental arm on the shaft meshing with the gearing on the frame, a plunger mounted on the under side of the car and connected to the gearing, an operating-lever connected to the operating-shaft, an elevator-landing door, a lock therefor arranged to be actuated by the plunger, and a lock on the wall of the elevator-well arranged to engage the plunger when the said plunger is projected and the door is opened, whereby the operating mechanism of the car is locked, substantially as described.

In testimony whereof I have signed my name to this specification in the presence of two subscribing witnesses.

JOHN S. MUCKLE.
